RAILWAY CAR TRUCK

Rudolph Leppla, Pittsburgh, Pa., assignor to
McConway & Torley Corporation, Pittsburgh,
Pa., a corporation of Pennsylvania

Original application December 31, 1942, Serial No.
470,788, now Patent No. 2,373,576, dated April
10, 1945. Divided and this application October
16, 1943, Serial No. 506,469

2 Claims. (Cl. 105—190)

This invention relates to railway car trucks of the type in which the bolster is yieldably supported by a spring plank suspended from a transom and more particularly to the means for suspending the spring plank from the transom.

This application is a division of my prior application Serial No. 470,788, filed Dec. 31, 1942, for Railway car truck, which has matured into U. S. Patent No. 2,373,576, granted April 10, 1945.

An object of the invention is to provide an adjustable seat between the transom and the spring plank supporting links, whereby the inclination of the links may be adjusted.

A further object is to provide bearing blocks for the pivots of the spring plank supporting links which are detachably mounted in the transom so that they may be readily replaced when worn or otherwise damaged.

With the above and other objects in view, the invention may be said to comprise a car truck as illustrated in the accompanying drawings, hereinafter described and particularly set forth in the appended claims, together with such variations and modifications thereof as will be apparent to one skilled in the art to which the invention pertains.

Fig. 1 is a fragmentary top plan view of the truck, with a portion of the side frame broken away and shown in section;

Fig. 2 is a vertical transverse section, through a side frame and ends of the transom bolster and spring plank, portions of the transom, spring plank and bolster being shown in side elevation.

Fig. 3 is a section taken on the line indicated at 3—3 in Fig. 2;

Fig. 4 is a fragmentary side elevation of one end of the transom and spring plank;

Fig. 5 is a section on the line indicated at 5—5 in Fig. 2.

In the accompanying drawings, one side portion only of the truck is illustrated, it being understood that the opposite side of the truck is identical with the side shown in the drawings.

The truck has side frames A, and transom B, a bolster C, and a spring plank D, the transom B being a cross frame member connecting the side frames A, and the bolster C being yieldably supported on the spring plank D, which is flexibly suspended from the transom. The truck side frames A are of a conventional freight car type, having top and bottom chords 1 and 2, that connect the journal boxes at opposite ends of the frame. In trucks of the type to which the present invention relates the weight of the car body supported on the truck is imposed upon

the bolster, transmitted through suitable cushioning means from the bolster to the spring plank suspended from the transom, and through the transom to the side frames, which impose the weight upon the car axles. Vertical guide columns 4 connect the top and bottom chords 1 and 2 and these columns are spaced apart to provide a central transom receiving opening in the side frame.

10 The transom B comprises a pair of spaced parallel cross beams 11 and integral end portions 12 which connect the cross beams 11. The cross beams 11 may have inwardly offset portions 13 at the ends which extend into the openings 5 of the side frames, and to which the connecting members 12 are integrally joined. The end members 12 have depending arms 14 at opposite ends thereof which are disposed at right angles to the cross beams 11. The cross beams 11, connecting members 12 and arms 14, are preferably tubular and of rectangular cross section joined together in a one-piece casting.

15 Adjacent the top thereof the end portion 12 of the transom is provided with laterally projecting guide lugs 15 and 16 which are adapted to straddle the guide columns 4.

20 Midway between their ends the parallel cross beams 11 are provided on their inner upper edges with arcuate recesses 24, which are adapted to receive a center bearing 25, which may be formed integrally on the bolster C. The recesses 24 are so proportioned that the center bearing 25 is permitted to have a limited amount of vertical play and also a limited amount of endwise movement in the recesses so that the bolster C may have corresponding movements. The bolster C is supported at its ends upon suitable springs, such as coil springs 26, which are shown mounted between top and bottom seating plates 27 and 28 25 on the under side of the bolster and on the spring plank D.

25 The recessing of the cross beams permits the use of straight cross beams and also serves the dual purpose of providing an additional lateral 30 limiting stop for the bolster as well as a vertical limiting stop to prevent the bolster springs from going solid.

The spring plank D has a saddle member 29 attached to the under side thereof at each end, 35 and each saddle member has laterally spaced, rectangular eye or loop members 30, which are adapted to receive a pivot bar 31. Each pivot bar 31 has a rounded top edge 32, which engages in concave bearings 33 on the under side of the saddle 29. The pivot bars 31 extend across the

under side of the spring plank, and the opposite ends thereof are seated in slots 34 formed in the lower ends of suspension links 35, the bars 31 having notches 36 on the under side thereof which are of a width to receive the links 35 at the lower ends of the slots 34, so that the bar 31 is restrained against endwise movements with respect to the suspension links.

The links 35 disposed on opposite sides of the spring plank D extend upwardly through slots 37 formed in the cross beams 11 and carry trunnions or pivot members 38 at their upper ends which rest in sockets 39 formed in bearing blocks 40, which are seated in recesses 41 formed in the tops of the cross beams 11. Each bearing block 40 has a central slot 42 through which the link 35 extends. The recesses 41 are preferably substantially rectangular in form, and the blocks 40 are shaped to fit in the recesses. Central portions of the recesses 41 preferably extend the full width of the upper faces of the cross beams 11, but adjacent the ends of the recesses 41 flanges 43 are provided on opposite sides thereof which engage in recesses on the under side of the blocks 40 and hold the blocks against lateral movements.

The pivot-receiving recess 39 of each of the blocks extends across the full width of the block and is disposed nearer one end of the block than the other. Each of the blocks is reversible in its recess, so as to adjust the positions of the recesses 39 toward or away from the transom end and to thereby vary the inclination of the supporting links 35.

In Fig. 4 the blocks 40 are shown in a position reverse to that shown in Fig. 2, so that the links 35 are disposed at an inclination. The blocks 40 are readily detachable and replaceable, and blocks may be provided with the recesses 39 at

various distances from the longitudinal center of the block, so that the desired adjustment of the links may be provided, either by reversing the blocks or by substituting bearing blocks. The provision of replaceable bearing blocks is advantageous for the additional reason that they may be replaced with new blocks when worn or damaged.

It is to be understood that variations and modifications of the specific devices herein shown and described for purposes of illustration, may be made without departing from the spirit of the invention.

What I claim is:

1. In a car truck, side frames, spaced cross frame members connecting said side frames and having recesses in the tops thereof adjacent their ends, a bearing block reversibly seated in each of said recesses, each block having a transverse bearing socket in its upper face nearer one end thereof than the other, suspension links having trunnions at their upper ends seated in said sockets and a spring plank carried by said links.

2. In a car truck, side frames, a transom supported in the side frames and comprising spaced parallel cross beams, said beams having transversely aligned recesses to the tops thereof adjacent each end of the transom and a longitudinal slot centrally of each recess, a bearing block in each recess having a central slot that registers with the beam slot and aligned bearing sockets upon opposite sides of the slot, each block being reversible in its recess and having its bearing sockets nearer one end than the other, links extending through the slots and having trunnions seated in said sockets, and a spring plank supported by the links.

RUDOLPH LEPPA.
